Attorney

UNITED STATES PATENT OFFICE

JOHN L. MOHUN, OF OMAHA, NEBRASKA

GRAIN-LOADING ARRANGEMENT FOR RAILWAY CARS

Application filed February 27, 1929. Serial No. 342,985.

This invention relates to railway freight train equipment, and particularly that class of equipment which is used to transport grains and similar lading, and has for its 5 object to provide an aperture in the roof of such a car to accommodate the grain loading chute, which aperture is automatically closed when the chute is removed. In an ordinary car when the present spouts from the grain 10 elevators are introduced through the side doors, in some cars, the car cannot be filled to its capacity on account of the space occupied by the chutes above the grain and the underside of the roof.

15 An object of this invention is to provide such an aperture with a door which automatically closes and which can be unlocked only from the inside of the car and to provide a lock therefor which cannot be jolted 20 by the service movements of the car into opened or unlocked position.

Another object of the invention is to provide such an opening which is large enough 25 to accommodate the standard chutes now in service but to also provide means to prevent the entrance of a thief through such opening.

In the drawings:

Fig. 1 shows a plan view of a typical 30 application of my invention.

Fig. 2 is a section on line 2—2 of Fig. 1.

Fig. 3 is a section on line 3—3 of Fig. 1.

Fig. 4 shows the relation of the apertures to the general plan of the car.

Fig. 5 is a detail showing the locking mechanism.

40 My invention comprises a preferably circular frame around the aperture which is provided with a horizontal flange 2 for attachment to the roof or roof sheet of the car, which sheet is preferably flanged outwardly.

(3) adjacent the perimeter of the aperture for weather-proofing and the upstanding wall 4 of the frame is rabbed to accommodate this flange so as to provide a smooth interior 45 surface for the aperture. Tar paper or other weather-proofing means may be inserted between the flange and the roof sheet. The frame is also preferably provided with an outwardly projecting horizontal flange 5 for weather-proofing. The door is provided

with a downwardly projecting flange 6 at its perimeter for weather-proofing. This door is hinged to the frame and the frame is provided with lugs 7 which restrict the opening movement of the door so that the door 55 cannot be opened to such a position that when released it will not automatically close; in other words, the door may be open far enough to permit the entrance of the chute but as soon as the chute is removed the door automatically falls to closed position.

A latch 10 is provided on the inside of the door which has an inclined surface 11 so that when the door is closing the latch is moved backwardly so that its tongue 12 automatically falls into the groove 13 in the frame. The lock to the latch comprises a gravity weight 14 slidably engaging grooves in the retainers 15. To open the door the weight is held in the position shown in Fig. 65 5 but as the latch swings into locked position the weight moves by gravity to the bottom of the slot, behind the latch, and retains the latch in locked position against jars 70 caused by impacts of the cars in service.

The aperture is partially closed by the bars 16 which project across it to prevent the entrance of a thief into the car. These bars are provided with a rounding top surface to prevent grain or other material from resting 75 thereon, which material might later be jarred off of the bars on to some perishable lading.

Fig. 4 shows a small plan of the top of a freight car and shows the preferred position of the loading apertures wherein one aperture is positioned on one side of the car adjacent the end and the other aperture is positioned on the other side of the car adjacent the opposite end. Other apertures may be used if desired.

80 In the arrangement shown the hinges 18 of the doors are positioned toward the ends of the car so that the chute may be moved from one aperture to the other without interfering with the door.

95 The accompanying drawings illustrate the preferred form of the invention, though it is to be understood that the invention is not limited to the exact details of construction shown and described, as it is obvious that 100

various modifications thereof within the scope of the claims will occur to persons skilled in the art.

I claim:

- 5 1. In a railway car, means to accommodate a grain loading chute comprising an opening in the roof of the car provided with a surrounding frame having a self-closing door and an automatic latch mounted thereon.
- 10 2. In a railway car, means to accommodate a grain loading chute comprising an opening in the roof of the car provided with a surrounding frame having an automatically closing door mounted thereon which is provided with an automatic lock which can be unlocked only from the inside of the car.
- 15 3. In a railway car, means to accommodate a grain loading chute comprising an opening in the roof of the car provided with a surrounding frame having an automatically closing door mounted thereon, and bars extending crosswise of the opening.
- 20 4. In a railway car, means to accommodate a grain loading chute comprising an opening in the roof of the car provided with a surrounding frame having an automatically closing door mounted thereon, and bars extending crosswise of the opening provided with rounding top surfaces to prevent grain
- 25 30 or other material from resting thereon.

JOHN L. MOHUN.
